UNITED STATES PATENT OFFICE.

EDWARD B. HESS, OF NEW YORK, N. Y., ASSIGNOR TO ROYAL TYPEWRITER COMPANY, OF HOBOKEN, NEW JERSEY, A CORPORATION OF NEW JERSEY.

WRITING-MACHINE.

No. 875,430.

Specification of Letters Patent.

Patented Dec. 31, 1907.

Application filed January 30, 1905. Serial No. 243,440. Renewed October 17, 1907. Serial No. 397,917.

To all whom it may concern:

Be it known that I, EDWARD B. HESS, a citizen of the United States of America, residing in the borough of Brooklyn, city and State of New York, have invented certain new and useful Improvements in Writing-Machines, of which the following is a specification.

This invention relates to line-lock devices of the class in which the type-bars are locked or prevented from reaching the printing point. It is shown associated with margin stop devices so that when the predetermined end of a line is reached the type-bars are automatically locked; and with tabulatory devices so arranged that when the carriage, in being jumped, is arrested, the type bars are locked to render impossible, at that moment should the operator depress the key, printing of the first character intended for the new column at the end of the line of the preceding column.

Heretofore various line-lock mechanisms of the character referred to have been proposed.

Applicant's organization involves a type bar intercepting device co-extensive with the curved assemblage of heads of the type bars of a visible writing machine, and is moved into the paths of the type bars in proximity to, or in other words, opposite the heads; and a peculiarity of construction wherein it differs from other type bar locks is that the segmental or curved interceptor hangs from pivots located above the assemblage of type bar heads, is normally held out of their paths by a suitable retracting device, such as a spring applied at any appropriate point in the mechanism, and is swung into the paths of the type bar heads. Preferably the interceptor is so swung into the paths of the type bar heads by the endwise draft of a link extending from one side thereof along the side of the machine beneath the platen to the rear of the machine and there operatively connected with appropriate devices acting to arrest the traverse of the carriage when the predetermined end of a line has been reached, and also to arrest the carriage when engaged by a tabulator stop.

The details of construction of the type bar locking devices and margin stop devices, as well as those of tabulating devices combined in this machine with the locking and margin

stop devices are hereinafter set forth in detail.

In the accompanying drawings which illustrate this invention in a form experience has shown to be practical and efficient, and which illustrate so much only of a front stroke writing machine as is deemed desirable to illustrate the invention. Figure 1 is a vertical longitudinal section; Fig. 2 is a similar view, showing additional parts and some of the parts in different positions; Fig. 3 is a rear view with various parts in section; Fig. 4 a detail partial plan of the carriage showing one end thereof in rear of the platen; Fig. 5 a detail perspective view of the type bar intercepting device and associated parts by which it is operated; and Fig. 6 a diagrammatic view indicating the relation of the margin stop and tabulator devices.

The platen 1 is appropriately mounted in the carriage end plates 2, shown as connected by front and rear cross bars 3, 4, the latter of which bears upon a roller 5 mounted in a bracket 5' on the frame. At the front the carriage runs on balls 6. The type-bars 7 suitably pivoted in a segment 8 below the platen extend toward the front of the machine, normally resting upon the segmental back stop or rest 9. In the keyboard frame 10, above the type-ends or heads of the type-bars, is pivotally hung a type-bar locking segment 11, co-extensive with the curved or segmental assemblage of type-bar heads, and normally swung toward the front of the machine out of their paths of travel of the type bars in their excursions to the printing point on the platen. At one side the locking segment 11 is connected by a link 12 with one arm of a bell-crank lever 13 pivoted at the rear of the machine, and having its other arm connected by link 14 with the movable member 15 of the two-part frame-stop of the margin and tabulator stop devices. This stop is located in rear of the platen and preferably in, or about in, the center of the machine. The part 15 is disposed vertically and pivoted, on an axis at right angles to the platen, upon the similarly disposed member 16 pivoted on an axis parallel with the platen, in a piece or bracket 17 secured to the rear plate 18 of the frame. The upper end of member 16, as shown is rectangular in plan, while 15 is thin or flat and has a limited movement to and from the side of part 16. A coiled

spring 19 having one end connected to the frame and the other to bell-crank 13 normally holds the part 15 away from 16 and by the thrust upon link 12 holds the locking segment 11 out of the paths of the type-bars.

The lower end 16' of the upright member or lever 16 extends, as at 16², toward the right hand side of the machine and has connected to its forwardly bent end the rear end of a link 20 the front end of which is connected to the vertically movable stem 21 of a finger-piece 22, to which is also connected the rear end of a link 23 whose front end is hinged to a fixed piece 24 on the stem guide-plate 25. A coiled spring 26 surrounding the link 20 has its front end attached to the link and its rear end to the back-plate of the frame and acts to hold the finger piece, and tabulator and margin frame-stop 15, 16, in normal, *i. e.* forward, position shown in dotted lines in Fig. 1 and in full lines in Fig. 2.

Extending between the plates 2 of the carriage is a margin stop-bar 27 having teeth on its upper surface and on which are mounted the adjustable carriage margin-stops or blocks 28, 28', each of which has side plates that straddle the bar and are connected below it by a pin 29; and pivoted in the top a spring latch 30 that engages the teeth on the bar. These blocks have reversely beveled rearwardly extending projections 31, and the one 28, to the left, by abutting against the member 16 of the frame-stop determines the left hand margin on the printed sheet, while the block 28' to the right, by abutment against the movable member 15 of the frame-stop, arrests the carriage when the predetermined length of line has been printed. When this latter action occurs the upper end 40 of the part or lever 15 is moved flatwise against the side of part 16, and the bell crank lever 13 is rocked to draw link 12 rearwardly and swing the segmental type-bar locking segment or frame into the paths of the type ends of the bars as illustrated by dotted lines in Fig. 2. If now the operator attempts to depress the finger pieces of any of the type-bars, the bars will be prevented from passing to the printing point by the locking segment 45 11. If, however, it be desired to print one or more letters at the end of the line the margin release key or finger piece 22 is depressed and link 20 draws the end 16² of the frame-stop member forward and rocks its upper end 16, together with the movable frame-stop member 15, rearwardly (Fig. 1) out of the path of the block 28', when, by reaction of spring 19 the type-bar locking segment is swung out of the paths of the type-bars. Now on the depression of a printing finger-piece, an additional letter is printed and the carriage fed forward. Any suitable universal bar and carriage feed devices, may be employed.

Combined with the devices described are tabulating devices arranged and operating

as follows. In rear of the margin stop toothed bar 27 and supported by the carriage end-plates 2, is a bar 32 having teeth 33 on its front face. Adjustably seated on this bar are removable tabulator stop-plates 34. 70 The above described rearward movement of the frame-stop 15, 16, to release the margin stop, is not sufficient to carry it into position to engage a tabulator stop plate, should one be in position.

In rear of the lower end 16' of the part 16 is a cam plate or wiper 35 carried by a rock-shaft 41 having at the side of the machine a radial arm 37 from which a link 38 extends to the stem 39 of a tabulator key or 80 finger piece 40. A spring 36 applied to the rock-shaft holds the wiper 35 retracted. Extending down alongside of the lever 16 is the lower end of an angular rack-bar release lever 42 pivoted at 43 in the frame bracket 5' 85 and from thence extending forward. Its front end has a flat lateral horizontal extension 44 to the upper face of which is attached a piece of leather or other friction producing material 45, above which is a rearwardly extending horizontal plate or flange 46 attached to or forming part of the carriage feed-rack 47 normally engaging the pinion 48 on the shaft of the escapement wheel 49. Attached to the ends of the rack are rearwardly extending arms 50 pivoted at 51 in the side plates 2 of the carriage and having applied to one (or each of them) a spring 52 that acts to normally hold the rack in engagement with the pinion. 162

When the tabulator key 40 is depressed the wiper 35 is rocked forward carrying with it the feed rack-bar release lever and the lever 16 and with it the laterally movable lever 15. The extent of movement is sufficient to carry the member 15 into position to engage the tabulator stop-plates, and is permitted by the slot 16² in the forwardly bent end of the part 16². When the printing in one column is finished, the tabulator key is depressed and the feed-rack being moved out of engagement with its pinion, the carriage moves forward subject to the breaking action of the surface 45 on the under face of the feed rack flange 46, until the part 15 strikes the next tabulator stop-plate 34, when the carriage will be arrested and the type-bar locking segment swung forward to lock the type-bars, so that if at that moment a printing key were depressed printing could not 110 occur. On release of the tabulator key the parts all return to normal position and printing in the next column may be proceeded with. 120

The stop member 15 is made thin and extends rearwardly beyond the part 16; and the rearward movement of the two is sufficient to bring the former, but not the latter, into engagement with the tabulator stops, which are also quite thin, and the construc- 125 130

tion is designed to be such as to have as little lost motion as practicable in the passage of the frame stop 15, 16, from normal position to that in which it will engage the tabulator stops. The shift to a new column may be made within two letter spaces, making printing in very narrow columns entirely feasible. The organization or adjustment is such that the carriage feed rack is first thrown out of engagement with its pinion and then a very slight rearward movement of the part 15 brings it into position to engage the tabulator stop next in position to arrest the carriage and throw the type bar locking segment across the paths of the type bars. The spring sustained part 15 also acts as a cushion to diminish its shock of impact against the tabulator stops.

The margin stop devices and such devices in combination with line lock devices are shown and claimed in my application Ser. No. 243,439, filed January 30, 1905: and the tabular devices and such devices combined with line lock devices and also with the margin stop devices are shown and claimed in my application Ser. No. 244,022, filed Feb. 3, 1905.

I claim as my invention:

1. In a writing machine, a platen and type bars pivoted below the platen and normally extending toward the front of the machine in combination with a type-bar locking-frame segmental in form and pivoted in a plane

above the type bar heads, normally swung forward at its ends out of the paths of the type bars but adjacent the type bar heads and adapted to be swung rearwardly into the paths of the type bar heads.

2. In a writing machine, a platen and type bars pivoted below the platen and normally extending toward the front of the machine, in combination with a type bar locking-frame pivoted in line vertically above the assemblage of type bar heads, normally swung forward into a plane adjacent to and in front of them and adapted to be swung rearwardly over them and into their paths.

3. In a writing machine a platen and type-bars pivoted in a segment below the platen and normally lying toward the front of the machine, in combination with a swinging type-bar locking segment curved to conform, substantially, to the curve in which the heads of the type-bars lie, pivoted at its ends above the type-bar heads and having its curved face adjacent the type-bar heads, said locking segment being normally swung forward out of the paths of and adjacent to the type-bars, and means for swinging it forward to lock the type-bar.

In testimony whereof, I have hereunto subscribed my name.

EDWARD B. HESS.
